CLAIM

The ornamental design for a luminaire, as shown and described.

DESCRIPTION

FIG. 1 is a top perspective view of a luminaire of the present invention;

FIG. 2 is a bottom perspective view of the luminaire of FIG. 1;

FIG. 3 is a left side elevational view of the luminaire of FIG. 1, the right, opposite, side of which is a mirror image thereof;

FIG. 4 is a front elevational view of the luminaire of FIG. 1, the rear, opposite, side of which is a mirror image thereof;

FIG. 5 is a top plan view of the luminaire of FIG. 1; and,

FIG. 6 is a bottom plan view of the luminaire of FIG. 1.
The broken lines shown are for illustrative purposes only and form no part of the claimed design.
